UNITED STATES PATENT OFFICE.

GEORGE E. BERGSTROM, OF CHICAGO, ILLINOIS.

DESIGN FOR A CLOTHES-CHEST.

59,057.

Specification for Design.

Patented Sept. 20, 1921.

Application filed February 28, 1921. Serial No. 448,598. Term of patent 14 years.

To all whom it may concern:

Be it known that I, GEORGE E. BERGSTROM, a citizen of the United States, residing at Chicago, in the county of Cook and State of Illinois, have invented a certain new, original, and ornamental Design for a Clothes-Chest, of which the following is a specification, reference being had to the accompanying drawings, forming part thereof.

The figure is a perspective view of a clothes chest.

I claim:

The ornamental design for a clothes chest as shown.

In testimony whereof I affix my signature.

GEORGE E. BERGSTROM.
